CLAIM

The ornamental design for a pizza container, as shown and described.

DESCRIPTION

FIG. 1 is a top perspective view of a pizza container showing my new design;

FIG. 2 is a top perspective view thereof, shown with the lid in a separated condition;

FIG. 3 is a bottom perspective view of that shown in FIG. 1;

FIG. 4 is a side elevation view thereof;

FIG. 5 is a side elevation view thereof, shown with the lid in a separated condition;

FIG. 6 is an end elevation view of that shown in FIG. 1;

FIG. 7 is an end elevation view thereof, shown with the lid in a separated condition;

FIG. 8 is a top plan view thereof; and,

FIG. 9 is a bottom plan view thereof.
